ABSTRACT OF THE DISCLOSURE

A quickly erectable tower crane comprises a lower chassis, a swivel ring fixed on the chassis and surmounted by a mast which may be of simple construction or made up of a plurality of telescopic parts and carries a jib at its upper end. A movable counterweight is pivotally connected to a point adjacent the lower part of the mast, elements being provided between this counterweight and the mast so that these two parts of the crane may be shifted relative to each other. This relative motion permits both a control of the mast erection when the counterweight rests upon the ground and a control of the counterweight erection so that it becomes operative for balancing the jib while the crane works.

This invention relates to a rapidly erectable work-site tower crane.

Rapidly erectable work-site tower cranes are generally constituted by a chassis upon which there is articulated a mast in two telescopic parts, which is intended to support the jib. For transportation this mast is brought down to the horizontal position. It then remains connected to the chassis by its articulation, the said chassis remaining in its normal position. The assembly is transported by means of wheels placed beneath the chassis and towards the end of the mast.

Such an arrangement produces a lengthy and cumbersome road-transport assembly, causing difficulty in the transport of the crane together with its ballast.

The purpose of the invention is to remedy the drawbacks of the known arrangements, and to permit the realization of a rapidly erectable tower crane which can be transported, with its ballast, in the form of a short and compact road-travel assembly.

The invention is carried into effect in a transportable tower crane comprising a lower chassis, a swivel ring fixed on this chassis and surmounted by a mast which may be of simple construction or formed from a plurality of telescopic parts and carries a jib at its top, and a counter-weight directly or indirectly articulated connected to a point disposed towards the lower part of the mast, elements being provided between this counterweight and the mast so that these two parts of the crane may be displaced in relation to one another.

The style of the articulation between the counter-weight and the mast is so designed that when the counter-weight has been lowered so as to rest on the ground or on a support surface, the mast can be moved by pivoting about the axis of articulation and can be brought down on to the counter-weight for transportation. In this position a carrier train is placed beneath the forward part of the mast constituted by the chassis. This forward part can for example bear upon a tractor, in which case an articulation having a vertical axis can be provided at this point. Another carrier train is also disposed towards the rear of the mast when it is in the horizontal position, preferably at the rear third of the length of the mast.

It can be seen that in this transportation position the mast, in the horizontal position, in fact serves as a carrier girder, beneath which the counter-weight can be fixed.

2

The utilization of this lowered mast as carrier girder produces a compact and simple assembly, and advantageously solves the problem of the transportation of the counter-weight or ballast. Moreover it will be noted that the fitting of the rear carrier train at approximately the rear third of the length of the mast gives a satisfactory distribution of loads, ensuring good adhesion of the rear wheels, while the whole can easily turn without cutting in too far and without the rear part, situated beyond the carrier train, overhanging too far.

The elements which effect the relative movement between the counter-weight and the mast can be constituted by one or more jacks, or by a block and tackle or similar device, occupying an appropriate position. In the case of a tackle-block a cable can be provided wound on a special erecting drum, driven by a suitable winch or combined with the hoisting winch of the crane, this winch being fixed preferably beneath the mast in the transportation position. This same block and tackle can if desired be extended to the interior of the mast in order to effect its telescopic movement during erecting.

When one or more jacks are used, constituting rigid control devices, the point of articulation between the counter-weight and the mast may be selected in any manner, for example axially of the mast. However in the case of a block and tackle, this articulation point is preferably brought towards the side of the mast which is directed upwards during transportation, permitting the mast of its own accord to descend again into the horizontal position under its own weight during the dismantling of the crane.

The lower chassis of the crane can be formed in a conventional way by a base and four arms articulated thereto, carrying bearing elements or translational movement elements (such as wheels or caterpillar tracks), while these arms can be folded to within the track width of the assembly for transportation.

In the case of small or medium-size cranes, the chassis is connected to the mast in such manner that during transportation it occupies a position perpendicular to its working position, the support arms of this chassis being folded upwards. However, in the case of heavy machines, by reason of the fact that the dimensions of the track and consequently the length of the arms increase, the height dimensions of the machine become too great for transportation. According to another particular feature of the invention the lower chassis is then constituted by a base upon which arms are articulated, and by a ball ring upon which a rotating chassis is mounted, and the latter serves as an articulation element for the mast, so that in the transport position the base retains its horizontal position, the arms being folded in the longitudinal direction of the assembly. The rotating chassis is then prolonged towards the rear, supporting the counter-weight, and towards the front in order to serve as a saddle for coupling to the tractor. A tackle-block provided between the rotating chassis and the mast renders it possible to raise the latter for erection. If desired, this tackle may be prolonged into the mast so as to serve for the telescopic movement thereof. In the transport position the counter-weight can be fixed on the mast by means of pegs and the mast then serves as carrier girder for the assembly. It will in particular be noted that in this case it will be advantageous to use a cast-iron counter-weight, the bulk of which is noticeably less than that of a current counter-weight.

According to yet another particular feature of the invention, in the case of very small machines which can be transported wholly on a vehicle, the counter-weight is articulated to the mast at a sufficiently high point so that the counter-weight may be deposited on the platform of a vehicle, for example, a lorry, and in the dismantling of the crane this counter-weight serves as support about which the mast is swivelled for the loading of the crane onto the

lorry, so that the crane loads itself, without an external energy source.

The invention will be further explained hereinafter with reference to the accompanying drawings, wherein:

FIGURE 1 is a partial elevational view of an embodiment of the tower crane according to the invention,

FIGURE 2 shows this tower crane in the transport position,

FIGURE 3 is a profile view of a tower crane according to a variant, in the transport position,

FIGURE 4 is a partial front view, showing the lower chassis of this crane in the transport position,

FIGURE 5 is an elevational view of the crane in the position for use,

FIGURE 6 is a plan view of the lower chassis in the position for use,

FIGURE 7 shows, in elevation, another embodiment corresponding to a crane which is transportable on a vehicle.

As represented in the drawings, the crane comprises a chassis 1, which is equipped in a manner known per se with articulated arms 2, on the ends of which there are provided support elements 3 resting on the ground during working, as indicated in FIGURE 1.

According to the invention, the central part of the chassis 1 is surmounted by a ball-type or roller-type swivel ring 4, which carries the mast 5 of the crane. In the present case this mast is of simple construction, but it could equally be constituted by a plurality of telescopic elements. The jib 6 of the crane is articulated at 7 to the upper end of the mast 5, in the usual manner.

The counter-weight of the crane according to the invention comprises a frame 8 into which the actual ballast 9 is fitted and which is articulated at 10 to the lower part of the mast 5, in the vicinity of the swivel ring 4. A jack 11 is interposed between a point 12 of the mast 5 immediately close to the ring 4 and another point 13 provided on the frame 8 of the counter-weight. During working, a connecting rod 14 intended to retain the counter-weight 8, 9 can be provided between the counter-weight and the mast 5. The action of the counter-weight is transmitted to the jib by cables 15.

On examination of the drawings it will be noted that a carrier train, formed by wheels 16, is here provided in a fixed position towards the upper part of the mast 5 when the latter is in the vertical position. However this carrier train could be removable.

According to the embodiment as represented, a tackle-block assembly, indicated at 17 in FIGURE 1, is provided between the mast and the counter-weight, the purpose of which assembly will be mentioned hereinafter.

The manner of operation of the assembly is as follows: Assuming that the assembly is in the transport position as shown in FIGURE 2, it will be noted that in this condition the mast 5 occupies a horizontal position, but remains fast with the chassis 1, which is itself in a position perpendicular to its working position, as may easily be seen from comparison of FIGURES 1 and 2. The arms 2 of the chassis 1 are then folded to within the road-travel track width. The jib 6 rests on the mast 5 and the counter-weight 8, 9 has been applied against the mast and is retained in this position by a peg 18. The forward part of the mast, which is constituted by the chassis 1, here rests on a tractor 19 through the intermediary of an articulation with a vertical axis, indicated diagrammatically at 20. This arrangement has been adopted to permit the jib to overhang the tractor if necessary, but the converse arrangement is equally possible.

It may be seen that in this position the mast 5 of the crane serves in fact as a carrier girder and that for transportation this crane constitutes a short and compact assembly, including the counter-weight, which is suspended beneath the mast.

When the assembly has arrived on site, erecting is effected in the following manner:

A jack is placed at the front beneath the chassis 1 and the tractor 19 is separated from the crane, then the latter is lowered until the front part of the counter-weight 8, 9 rests on the ground. The jack is then removed and the peg 18 is disengaged.

The jack 11 is then operated. When this jack shortens, the rear part of the counter-weight 8, 9 first comes into contact with the ground. Then the assembly formed by the mast and the chassis bears on the counter-weight 8, 9, which rests wholly on the ground, and pivots about the point 10 in order finally to arrive at the vertical position. The support arms 2 are then unfolded and locked. The position obtained may be seen from FIGURE 1, the counter-weight 8, 9 then being in the position indicated in dot-and-dash lines in FIGURE 1.

The jack 11 is then operated afresh, in the opposite direction to the previous. As the chassis 1 is locked in the working position by the unfolded support arms 2, the assembly of mast and chassis has sufficient stability to cause the raising of the counter-weight 8, 9.

The relative movement of the counter-weight and the mast is utilized either to cause the telescopic movement of the elements of a mast in a plurality of parts, or to raise the jib with the aid of the tackle-block assembly 17 provided between the mast and the counter-weight. It will further be noted that the counter-weight 8, 9 by its mass assists the jack 11 to pull upon the tackle-block assembly 17. It is seen that the erecting of the crane is extremely simple and rapid.

The working position of the assembly is represented in FIGURE 1. Converse operations permit of returning the assembly into the transport position.

In the case of heavy machines, it can occur that the masses of the machine and counter-weight are too great to permit transportation by road as one single assembly. In this case the position of the counter-weight parallel with the ground and in its immediate vicinity permits of instantaneous depositing of the counter-weight with the aid of the lifting jack. In this case the counter-weight can be constituted by easily transportable blocks which can be assembled rapidly on the frame 8 shifted by the jack. In order to facilitate the operation, a passage is provided between the wheels 16 of the carrier train fixed on the mast, so that the machine can be moved while the ballast is left on the ground, and similarly can be brought to the lifting position, passing over the ballast, in reverse.

Yet another advantage can be obtained from the movement of the counter-weight. In effect, in the case of a crane having a raisable jib, where the variation of radius is effected by modifying the inclination of the jib, the movement of the latter can be effected easily by moving the counter-weight, provided that the associated mechanisms have been designed accordingly. It will be noted that this movement requires only slight power, since the dead weight of the jib is balanced by that of the counter-weight.

If it is desired to obtain a possibility of shifting the crane from one point to another on one and the same working site, the counter-weight 8, 9 can be replaced by a Caterpillar track assembly or another all-terrain movement assembly, ballasted in a suitable way. When the crane has been brought by road to the site, in the transport position as shown in FIGURE 2, it is set on the Caterpillar-tracked assembly. The pneumatic-tired carrier trains are then removed and the machine can shift on the site from one point to the other, after folding.

According to the embodiment represented in FIGURES 3 to 6, the crane comprises a lower chassis 1 associated with articulated arms 2 which, as may be seen especially from FIGURE 4, are raised vertically for transport so as to be situated within the road-travel track width. In this case also the mast 5 of the crane, serving during transportation as carrier girder beneath which the counter-weight or ballast 9 is placed, is connected to the chassis 1 through the swivel ring 4. This mast, form-

ing a carrier girder, rests towards the rear third of its length upon a rear carrier train 16, while the forward part of the assembly rests upon a tractor 19, as described with reference to the previous embodiment. The jib 6 of the crane is here again articulated at 7 to the mast.

According to this embodiment, the articulation point 21 of the counter-weight 9 on the mast 5 is brought to the upper side of the mast when the mast is in the transport position, and the counter-weight 9 is connected by a cable or tackle-block assembly 22 to the drum of a winch 23 placed beneath the mast in the horizontal position and passing over a return pulley 24 provided at the foot of the mast.

The manner of use of this crane is similar to that described above. Thus for the erection of the crane, once the counter-weight 9 has been deposited on the ground, the winch 23 is operated so as to wind up the cable 22, causing the mast 5 to pivot about the articulation point 21 into a vertical position. In this position the articulated arms 2 of the lower chassis are then extended to occupy the position represented in FIGURES 5 and 6. The operation of the winch then permits of raising the jib and the counter-weight, and of telescopically extending the elements of the mast 5 if the latter is in a plurality of parts.

For dismantling, once the counter-weight 9 has been lowered to the ground and the arms 2 have been folded, the offset articulation point 21 permits the mast 5 to serve as drive element for turning to the horizontal position, and the cable 22 and winch 23 then serve simply to brake this movement.

According to the embodiment represented in FIGURE 7, the crane is of small dimensions and has a total weight permitting it to be transported on a vehicle such as a truck 41. This crane is similar to that represented in FIGURES 1 and 2. However, the point 42 of articulation of the counter-weight 9 on the mast 5 is placed sufficiently high to enable the counter-weight to be placed on the platform of the truck 41 as shown. This articulation point is preferably placed at the center of gravity of the assembly formed by the mast 5, the jib 6 and the lower chassis 1.

The crane represented in FIGURE 7 comprises an erecting winch 43, which is fixed on the mast 5 beneath the articulation point 42 and so as to be situated beneath the mast when the latter has been turned to the horizontal position.

In FIGURE 7 there is indicated in solid lines the transport position, into which the mast 5 is turned down upon the counter-weight 9, which itself rests on the platform of the truck 41. In this position, the mast is fixed on the counter-weight through a connecting rod 44. On arrival at the working site the mast 5 is pivoted into the vertical position and the arms 2 are unfolded from the chassis 1. The height of the articulation point 42 is so calculated that in this position only the rear wheels 45 of the chassis 1 rest on the track intended to receive the crane, the front wheels 46 remaining slightly above this track. At this moment the erecting winch is operated, which extends the mast 5 and at the end of that travel raises the jib 6, which is held by a tie rod fixed to the counter-weight. Then the trolley of the crane is brought to the end of the jib, the hook is lowered and a sufficient load is raised so that the assembly rocks slightly about the lower edge 47 of the counter-weight 9, so that the front wheels 46 of the chassis come into contact with the track. The counter-weight 9 then rises sufficiently to permit securing of the connecting rod 48 upon the mast 5. The position obtained is then that indicated in dotted lines in FIGURE 7. The vehicle may then be removed.

Modifications can be made in the embodiments described, within the scope of technical equivalence, without departing from the scope of the invention.

What is claimed is:

1. In a transportable tower crane comprising a lower chassis, a swivel ring fixed on said chassis, a mast having a top portion and a lower portion, surmounting said swivel ring, and a jib provided at said top portion of said mast; a counter-weight articulatedly connected to a point on said lower portion of said mast for vertical swinging movement relative to said chassis and mast and jib, and actuating means provided between said counter-weight and said mast for moving the same with respect to each other and with respect to said chassis.
2. In a transportable tower crane comprising a lower chassis, a swivel ring fixed on said chassis, a mast having a top portion and a lower portion surmounting said swivel ring, said mast being movable between a vertical working position and a horizontal transport position, and a jib hingedly connected to the top portion of said mast; a counter-weight articulatedly connected to a point on said lower portion of said mast for vertical swinging movement relative to said chassis and mast and jib, and actuating means provided between said counter-weight and said mast for moving the same with respect to each other and with respect to said chassis said counter-weight being, in said transport position of said mast, secured beneath said mast.
3. A transportable tower crane according to claim 2, comprising a front carrier train and a rear carrier train detachably located beneath said chassis and beneath said mast in the horizontal transport position, respectively.
4. A transportable tower crane according to claim 1, comprising jacks mounted between said counter-weight and said mast for relatively moving the same.
5. A transportable tower crane according to claim 1, comprising a cable forming a tackle-block assembly and a winch secured on a side surface of said mast for relatively moving said mast with respect to said counter-weight.
6. In a transportable tower crane comprising a lower chassis, a swivel ring fixed on said chassis, a mast having side surfaces, a top portion and a lower portion surmounting said swivel ring, and a jib provided at said top portion of said mast; a counter-weight articulatedly connected to a point on said lower portion of said mast for vertical swinging movement relative to said chassis and mast and jib, the mast being movable between a vertical working position and a horizontal transport position, said articulation point being located near the side surface of said mast which is directed upwards when said mast occupies a horizontal position, a cable forming tackle-block assembly and a winch secured on the side surface of said mast which is directed downwardly when said mast occupies said horizontal position for relatively moving said mast with respect to said counter-weight, and means for swinging said counter-weight vertically relative to said chassis.
7. In a transportable tower crane comprising a lower chassis, a swivel ring fixed on said chassis, a mast having a top portion and a lower portion surmounting said swivel ring, said chassis, swivel ring and mast being rigidly connected so that said mast constantly occupies a position perpendicular to said chassis, and a jib provided at said top portion of said mast; a counter-weight articulatedly connected to a point on said lower portion of said mast for vertical swinging movement relative to said chassis and mast and jib, and actuating means provided between said counter-weight and said mast for moving the same with respect to each other and with respect to said chassis.
8. In a transportable tower crane having sufficiently small dimensions and weight to permit its transportation on a vehicle, comprising a lower chassis, a swivel ring fixed on said lower chassis, a mast having a top portion and a lower portion surmounting said swivel ring, and a jib hingedly connected to said top portion of said mast; a counter-weight articulatedly connected to a point on

said lower portion of said mast for vertical swinging movement relative to said chassis and mast and jib, actuating means provided between said counter-weight and said mast for moving said mast with respect to said counter-weight between a vertical working position and a horizontal transport position, said articulation point provided on said mast being located at a level which is higher than a vehicle platform that serves for transporting the crane but substantially below the top of the mast in such a manner that on operation of the actuating means the mast turns down on to the counter-weight and thus the crane loads itself on to the vehicle, and means for swinging said counter-weight vertically relative to said chassis.

5

9. A transportable tower crane according to claim 8, wherein said articulation point is located at the center of gravity of the assembly formed by said mast, jib and chassis.
